CLAIM

The ornamental design for a safety glasses carrying pouch, as shown and described.

DESCRIPTION

FIG. 1 is a front elevational view of the safety glasses carrying pouch showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of the safety glasses carrying pouch.

The broken line showing of legible matter in FIGS. 1 and 7 is for illustrative purposes only and forms no part of the claimed design.
